UNITED STATES PATENT OFFICE.

WILLIAM ALBERT HICKMAN, OF NEW LONDON, CONNECTICUT.

BOAT.

Application filed September 25, 1924. Serial No. 739,837.

To all whom it may concern:

Be it known that I, WILLIAM ALBERT HICKMAN, a subject of the King of Great Britain, and a resident of New London, county of New London, State of Connecticut, have invented an Improvement in Boats, of which the following description, in connection with the accompanying drawings, is a specification, like characters on the drawings representing like parts.

This invention relates to boats and more particularly to the propulsive systems thereof and the object is to provide an improved and more efficient method of propelling vessels. The invention will be readily understood in view of the following description taken in connection with the accompanying drawings wherein:

Fig. 1 is a plan view of a boat shown for illustrative purposes exemplifying a form of the invention;

Fig. 2 is a quasi-diagrammatic view illustrating in side elevation the stern portion of the boat shown in Fig. 1;

Figs. 3 and 4 are similar views;

Fig. 5 is a stern elevation of the boat shown in Fig. 4; and

Fig. 6 is a diagram to be referred to.

The system of boat propulsion herein described involves the use of a so-called surface or semi-submerged propeller wherein the shaft bearings and supporting struts and preferably also the less efficient innermost portions of the blades are disposed above the surface of the water in which the boat travels. This is usually effected by providing a propeller on a shaft disposed parallel to and above the normal water line when the boat is at speed, the blades of the propeller dipping into the water below the shaft as the shaft revolves. Such an arrangement of a propeller utilizing the direct propulsive effect of the useful driving portions of the propeller blades, say the outermost two-thirds of the length of the blades, and eliminating the retarding force of driving through the water those submerged parts which in the ordinary submerged screw propeller system are necessary for carrying the useful parts of the blades, to wit, the innermost thirds of the blades, the hub of the propeller, the propeller shaft, bearings and struts, has demonstrated high propulsive efficiency in boats of widely varying types and particularly in boats running at high

speed and, when driven by an engine of given power, such a propeller can be turned at the same number of revolutions as a submerged screw propeller although having a considerably larger submerged area. It will be realized, however, that in the propeller of the surface type only a portion of the blade area is passing through the water at any given time. The ideal condition for propulsion would obviously be a propeller in which the outer portions of all the blades were submerged and acting simultaneously while the inefficient inner portions, the hub and the mechanism organized adjacent the center of the propeller which would cause retardation were not present, but such a construction is obviously an impossible abstraction.

In the accompanying drawings I have illustrated by way of example merely a type of boat similar to that shown in my Patent No. 1,204,355, dated Nov. 7, 1916, but not, however, because the scope of the invention is limited to that type of hull. On the contrary, it is applicable to hulls of widely differing types and to relatively slow boats or boats of large displacement as will appear as the description proceeds.

Referring to these drawings I have there-in illustrated a boat having a hull 7 provided with an inverted V-shaped bottom, the V gradually flattening from forward to aft and merging adjacent the stern transom 11 in a flat or substantially flat transom bottom 13. The boat is adapted to be driven by a surface propeller 15 arranged on a propeller shaft 17 extending substantially parallel with the normal water line of the boat, this being the most efficient angle for driving the boat forwardly through the water as will be well understood. Obviously for constructional reasons, the shaft 17 is a certain distance above the bottom 13 of the stern transom and, if the propeller 15 were hung directly aft of the transom 11, only the outermost portions of the blades would dip below the level of the bottom edge 13 thereof.

A speed boat of the type illustrated when travelling tends gradually to rise toward the surface of the water as the speed increases owing to the structure of the under-body and at high speed there will be but slight displacement by the hull and the shaft 17 will be raised correspondingly above the surface of the water compared with its position

when the boat is at rest or moving at a moderate rate of speed. The water will flow out beneath the transom 11 leaving the bottom edge 13 thereof at a point considerably below the normal level and curve upwardly toward and above the normal surface forming a wave as illustrated more or less diagrammatically by either of the lines L and H in Fig. 2. The straight or relatively straight edge 13 of the stern transom 11 is an example of a surface of a boat's hull which delivers aft a sheet of water rising rearwardly in the form of a wave.

The location of the crest of the wave with respect to the transom 11 will vary in accordance with the speed of the boat and the height of the wave will vary in accordance with the boat's displacement, the height of said wave as well as the distance of its crest from the transom being due to the inertia of the water. The form of the wave is susceptible of accurate calculation for any given set of conditions. Its height will vary with the speed and be practically fixed for any given speed. For example, the boat travelling at five miles an hour, the water might be two inches above the bottom line 13 of the transom six inches aft therefrom, while twenty inches aft it might be ten inches above the level of said line 13. At thirty miles an hour at a point six inches behind the stern transom, instead of being two inches above the line 13, might be only one-eighth of an inch, and twenty inches behind the transom, instead of being ten inches above the bottom, it might be only one and a half inches above this level. The inertia of the water will, of course, regulate this height depending entirely upon the speed of the boat.

In Figs. 2 and 3 I have illustrated without any attempt at dimensional accuracy a curve marked L representing the surface of the water when the boat is running at a relatively low speed and a curve marked H representing the surface of the water when the boat is moving at a relatively high speed.

It will be obvious that if the propeller 15 were hung directly aft of the transom 11 in Fig. 2 the total effective area of the blades when the boat is in motion would be small because the shaft 17 is necessarily higher than the bottom line 13 of the transom and the propeller cuts the wave which is developed substantially at its trough. In accordance with my invention, therefore, the shaft 17 is so extended that the propeller 15 is hung at a substantial distance aft from the transom 11 of the boat to intersect the rising wave at a point remote from its trough and in the vicinity of its crest so that the major portion of the effective surface of the propeller blade will cut through the water. Thus in Fig. 2 the propeller 15 is shown as so hung as to dip substantially

its entire surface in the low speed wave L, the hub and retarding inner portions of the propeller, however, being disposed above the water surface and the propeller acting as a surface or semi-submerged propeller. If the speed of the boat increases so that the wave developed takes the form H, the dip of the propeller is obviously diminished as the crest of the wave recedes. In fact, the dip of the propeller may be said to be automatically decreased by the dropping astern of the crest of the wave.

In application to boats of very high speed this automatic regulation of the dip of the propeller may be of considerable advantage. In this instance the propeller may be placed very far behind the line 13, for instance, six or seven feet, the crest of the wave in such a boat being far astern. The surface propeller intersecting this wave remote from its trough will have sufficient submerged area to permit the boat to be driven against its high resistance at a low speed while at top speeds, when the resistance of the boat is low, the area of the propeller blade engaging the water will be the minimum amount necessary to drive the boat having in view the very high relative inertias of the water at such speeds.

If, however, it were desired to provide a propeller which would dip comparatively deeply at a relatively high speed, in other words, to engage the wave H close to its crest as shown in Fig. 3, which would be desirable more particularly in boats of moderate speed or relatively great displacement, it will be seen from inspection of Fig. 3 that this might submerge the hub of the propeller in the wave L generated at low speed and that the surface propeller would then not function as such and there would be a great loss of efficiency at the low speeds or when starting when the resistance of the boat is greatest. To permit the mounting of the propeller in such a position as shown in Fig. 3 and to avoid this difficulty I may utilize the construction shown in Figs. 4 and 5 where I have provided an extension from the planing surface of the boat 19 extending aft from the line 13 which develops the rearwardly rising wave, which surface prevents the rising of this wave in the line of the propeller shaft. At either side of the propeller shaft the surface 19 may merge into buttock portions 21 upwardly directed to permit the rising of the wave laterally adjacent the outer or active portions of the propeller blades. The part 19 is practically an extension aft of the bottom of the boat and in the case of a planing boat must be looked upon as a portion of the actual planing area of the bottom and calculated with the proper buttock lines for this purpose. The surfaces 19 and 21 may be incorporated with the hull proper of the

boat in any suitable manner and herein are shown as planes supported by struts 23 from the rear transom 11.

The operation of the construction shown in Figs. 4 and 5 will be readily understood and the preceding discussion made clearer by reference to Fig. 6 illustrating diagrammatically a propeller as viewed from the rear. If line *a-a* represents the level of the water adjacent the lower edge of the transom 11, it will be clear that the propeller acting closely adjacent this transom would dip into the water a relatively small portion of the blade. Suppose, however, the propeller to be hung further aft as shown in Fig. 3 and the line *b-b* to represent the height of water of wave *H* at the location of the propeller. It is clear from the figure that a much greater portion of the propeller blade acts on the water. Now if a line *c-c* represents the height of the wave *L* at the same position, the hub of the propeller would normally be submerged with disadvantageous results. By virtue of the construction of parts 19 and 21 as herein described, the wave is, as it were, divided and prevented from rising in the vicinity of the shaft and takes substantially the form indicated by the line *d-d-d*. It is thus diverted from the hub and its bearings and the other portions of the propeller which if submerged detract so much from its efficiency while the outer portions of the blades, as will be clear from the diagrammatic figure, are operating in a depth of water rising to the line *c-c*. Thus, in the position of the figure two blades are simultaneously effective, whereas a single blade would be operating if the height of water were at the level *b-b*. As applied more particularly to boats of medium speed the arrangements described permit the use of surface propellers of relatively small diameter which nevertheless will have the same or even greater absolute area submerged than larger propellers mounted in the conventional position. This will permit engines of a given piston displacement to run efficiently at a higher number of revolutions per minute in hulls of a given weight and resistance.

I have described certain specific applications of the principles of my invention whereby the same may be put into practice. It will be understood that these exemplifications are for illustrative purposes only, the scope of the invention being defined by the following claims.

Claims—

1. A high speed motor boat having a hull formed to deliver aft a sheet of water rising as a wave governed by the inertia of the water and a surface or semi-submerged propeller hung at such substantial distance aft from said surface as to cut the wave remote

from its trough defined by the surface and where its height substantially changes due to variations in speed whereby an automatic variation in dip is effected to correspond with the increase in the relative inertia of the water at increased speeds. 70

2. A motor boat having a surface or semi-submerged propeller, a hull having a surface forward of said propeller to develop a rearwardly rising wave, said propeller being hung aft of said surface to engage said wave, at a determined speed of the boat, at a substantial distance from the trough of said wave to permit maximum submergence of the effective portion of the 75 blades. 80

3. A motor boat having a hull provided with a surface to deliver a sheet of water aft rising as a wave governed by the inertia of the water, a propeller hung relatively far 85 aft of said surface with its hub substantially at the same depth and means to prevent the rising of the wave in such manner as to submerge said hub while permitting such rising at the blades. 90

4. A motor boat having a surface or semi-submerged propeller and having surfaces incorporated with the hull of the boat which are so shaped as to deliver rearwardly separated waves directed to the blades of the 95 propeller away from the hub thereof.

5. A boat having a hull having a bottom portion, a surface propeller hung aft of said bottom portion, a surface forward of said propeller to develop a flow of water 100 and buttocks for guiding said flow from said surface to the outer portions of the propeller blades.

6. A motor boat having a surface or semi-submerged propeller, a surface forward of 105 said propeller to develop a wave rising rearwardly, said surface being continued aft along the center line of the propeller to prevent rising of the wave to submerge the hub thereof. 110

7. A motor boat having a surface propeller hung aft thereof at a substantial distance to engage the rising wave left astern by the boat as it advances at a point where its height substantially varies on changes of 115 speed of the boat, whereby a decreasing dip is procured as the speed of the boat increases.

8. In a motor boat, a surface propeller disposed at a distance astern of said boat and having a maximum dip at a point substantially coincident with the crest of a wave produced by the inertia of a stream of water flowing from beneath the boat when the latter is travelling at a given speed, said dip being automatically decreased as the speed of the boat increases and the crest of said wave is moved astern by inertia of the water. 120

9. A motor boat comprising a hull, a surface propeller arranged at a substantial dis- 130

- tance astern of said hull to effect a maximum submersion of said propeller at a given speed of the boat and means to direct the stream of water flowing aft from said 5 hull into engagement with the more effective propulsive portions of said propeller.
10. A motor boat comprising a hull having a transom stern, and a surface propeller arranged aft of said transom in substantial 10 spaced relation thereto, the blades of said propeller having a maximum degree of submersion when the boat is moving at a predetermined moderate speed and a minimum degree of submersion when moving at top 15 speed.
11. In a motor boat, a hull having a transom stern, and a surface propeller disposed aft of said transom substantially coincident with the crest of a wave produced by the 20 boat when traveling at a given speed.
12. In a motor boat, a hull having a transom stern, a surface propeller arranged aft and in selected spaced relation to said transom and means to guide the stream of water 25 flowing from beneath said transom to the propulsive areas of the blades of said propeller.
13. In a motor boat, a hull having a transom stern, a surface propeller arranged aft 30 and in selected spaced relation to said transom and means constituting a continuation
- of the bottom of said hull adapted to guide the stream of water from beneath said hull to the more effective propulsive areas of said propeller. 35
14. In a motor boat, a hull having a transom stern, a surface propeller arranged aft and in selected spaced relation to said transom and means constituting a continuation 40 of the planing surface of said hull adapted to direct the stream of water flowing from beneath said hull to effective portions of the blades of said propeller, cutting said blades at opposite sides of the axis of said propeller and in a plane substantially above said axis. 45
15. A motor boat having a surface propeller at the stern and a rearwardly extending plate underlying the shaft and extending adjacent to the propeller to intercept and break the wave of water flowing aft 50 from the bottom of the boat whereby to divert it from the central portion of the propeller.
16. A motor boat having a surface propeller at the stern thereof adapted to engage the rising wave of water in the wake of the boat and a water-break adjacent the shaft 55 to divert the water from the central portion of the propeller.

In testimony whereof, I have signed my 60 name to this specification.

WILLIAM ALBERT HICKMAN.
